UNITED STATES PATENT OFFICE.

WILLIAM H. PENNOCK, OF MERMAID, DELAWARE.

CULTIVATOR.

SPECIFICATION forming part of Letters Patent No. 275,260, dated April 3, 1883.

Application filed December 2, 1882. (No model.)

To all whom it may concern:

Be it known that I, WILLIAM H. PENNOCK, a citizen of the United States, residing at Mermaid, in the county of New Castle and State of Delaware, have invented certain new and useful Improvements in Cultivators; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a side view of my cultivator. Fig. 2 is a top or plan view of the same, and Fig. 3 is a side view of the draft-beam detached from the cultivator.

My invention relates to cultivators; and it consists in constructing and applying in that class of cultivators arranged for lateral adjustment a locking-latch of peculiar form and qualities, as hereinafter described and claimed.

Referring by letter to the accompanying drawings, *a* designates the draft-beam, the front end of which is provided with a clevis, *b*, and the rear end of which is provided with the cross-arms *c* and *c'*, secured thereto by a rivet, *d*, passed through a vertical eye, *e*, formed thereon. From the upper cross-arm, *c*, rise the braces *f*, which stay the handles *g*, the forward ends of which are secured to the draft-beam *a* by a bolt, *h*. Near the forward end of the draft-beam *a* a series of perforations, *i*, are provided.

k designates a sliding T-arm, having the base of its stem *l* slotted at *m*, and the prongs *m'* formed by making the slot *m*, bent downward, forward, upward, and rearward, to form eyes *n* *n'*, which correspond in size with the perforations *i*, and are intended to register with any one of said perforations *i*. A bottom plate, *o*, is also used in connection with the T-arm for a purpose to be hereinafter explained.

p *p'* designate the side beams, which are each formed of two sections, *p* *p'*, connected together by pivots or hinges *q* *q'*. The rear ends

of the rear or short sections, *p* *p'*, are hinged between the cross-plates or arms *c* *c'* at the rear of the draft-beam, as shown, while the front ends of the longer sections *p* *p'* are pivoted or hinged between the cross-head *i* of the T-arm and the bottom plate, *o*, the construction at this point being such that the T-arm may slide on the draft-beam *a*.

s designates the locking-latch, which is constructed of a rod or strong wire bent to form a lateral pin, *t*, at one end, and a vertical inverted-U clamp, *t'*, at the rear end. It is obvious that this latch is adapted for use in other portions of the cultivator—for example, in fastening the adjustable plow-standards to the cultivator side beams.

u designates the cultivator-standards, which are curved, as shown, and are secured near their upper ends to the draft-beam and side beams by pivot-bolts *u'*. These shanks or standards are also perforated at their upper ends, and corresponding perforations are made in their respective beams for the reception of wooden break-pins, which are intended to permit the standards to yield when the plows meet with an obstruction that would otherwise cause them to be broken. The lower ends of the standards are perforated from front to rear to receive the bolts by which the cultivator blades or plows are secured thereto. These plows or teeth *v* are made with double points—that is to say, they are nearly elliptical or diamond shape in edge outline, and are concavo-convex in surface outline, so that when in place on the standards they will conform to the curves of the latter. When one of the points has been worn away by use the plow may be reversed by withdrawing the bolt, turning the point that has been uppermost down, and again replacing the bolt.

This construction presents a cheap, simple, and durable cultivator. The side beams may be extended or contracted to suit the work to which the implement is to be applied by simply lifting the clamp *t'* from the draft-beam, removing the lateral pin *t* from the perforation *i* and the eyes of the T-arm, and sliding the latter in the direction desired on the draft-

beam, and again replacing the locking-latch. The plows may be reversed, as before stated, when worn.

Having thus fully described my invention, 5 what I claim as new, and desire to secure by Letters Patent, is—

In combination with a cultivator-beam, the locking-latch *s*, having the lateral pin *t* and

the vertical clamp *t'*, substantially as specified.

In testimony whereof I affix my signature to

in presence of two witnesses.

WILLIAM H. PENNOCK.
